UNITED STATES PATENT OFFICE

2,553,370

METAL HAIR CLIP

William Huppert, New York, N. Y., assignor to
 Kenore Products Corporation, New York, N. Y.,
 a corporation of New York

Application December 5, 1947, Serial No. 789,874

1 Claim. (Cl. 132—48)

1

My present invention relates to improvements in hair clips.

Pursuant to the invention, the hair clip comprises a plate member with which at one end is integrally connected a tongue member, the opposite end of the plate member being provided with a catch member for releasably holding the free end of the tongue member.

The invention is applicable for a plate member which is provided with a longitudinally extending slot and for a non-slotted corrugated plate member.

The hair clip is worn by the user by applying it to a strand of hair, the tongue member being inserted under the strand, the free end of the tongue member being locked by means of the catch member.

Pursuant to the slotted plate member embodiment of the invention, the tongue member is provided at its inner face with a convex corrugation, and has a width greater than the width of the slot; upon application of the hair clip to a strand of hair, the strand is therefore brought above the plane of the opposite longitudinal elements of the slotted member by virtue of the stated corrugations of the tongue member, whereby a ridge is formed in the hair.

Pursuant to the non-slotted plate embodiment of the invention, the strand of hair, when the hair clip is in its locked position, is disposed between the concavely formed underface of the plate member and the convexly formed upper face of the tongue member.

In the slotted embodiment and in the non-slotted embodiment the hair which is gripped between the inner faces of the hair clip is offset, thus preventing lateral displacement of the hair clip.

The non-slotted and slotted plate members are each of arcuate configuration of a given radius, conforming generally to the curvature of the human head, and its tongue members also of an arcuate configuration but of a greater radius at its central portion and of lesser radii at its opposite ends thus affording an enhanced pressure engagement over an enlarged arc between the tongue member and the underface of the non-slotted plate member, the hair of the strand being interposed therebetween, thus affording an assured locking of the hair clip relative to the strand of hair.

Further features and objects of the invention will be more fully understood from the following detailed description of the accompanying drawings, in which:

2

Fig. 1 illustrates generally an application of a hair clip pursuant to the invention, applied to a strand of hair of the illustrated female user; the embodiment of hair clip indicated in Fig. 1 is that of the slotted plate type;

Fig. 2 is a top plan view of the slotted plate embodiment of the invention, indicated in Fig. 1;

Fig. 3 is a side elevational view of Fig. 2, the tongue member being shown in its closed position;

Fig. 4 is a bottom plan view of Fig. 3;

Fig. 5 is a detail sectional view taken on line 5—5 of Fig. 3, on a somewhat enlarged scale, and additionally illustrating a strand of hair embraced by the hair clip;

Fig. 6 is a perspective view of the hair clip shown in Fig. 2, the tongue being illustrated in its open position;

Fig. 7 is an edge view of a non-slotted embodiment of the invention, the tongue being shown in its closed position;

Fig. 8 is a bottom plan view of Fig. 7;

Fig. 9 is a side elevational view of Figs. 7 and 8, the tongue member being shown in its open position; and

Fig. 10 is a detail sectional view taken on line 10—10 of Fig. 7, on a somewhat enlarged scale, and further illustrating a strand of hair interposed between the tongue member and the non-slotted plate member.

Referring to the drawings, and particularly Figs. 1 through 6, the hair clip is designated generally 20. This type of embodiment comprises a slotted plate member 21, its slot 22 being shown disposed substantially centrally and extending longitudinally of the plate member. The longitudinal elements 23, 24, of the plate member 21 are of arcuate configuration corresponding generally to the curvature of a human head.

The tongue member 25, as appear clearly from Fig. 6, is pivotally integrally connected at the end element 21a of the plate member 21. At the end element 21b of the plate member is provided a catch member 26 of suitable arcuate configuration for readily enabling the free end 25a of the tongue member to resiliently pass the free end of the catch member 26 when the tongue member is moved into its closed position, the curvature of the free end 25a of the tongue member cooperating with the curved formation of the catch member 26 to adjustably resiliently hold the tongue member in its locked position. Such adjustment of the locking of the tongue member affords variant locking positions of the tongue

member when the hair clip is applied to variant thicknesses of strands of hair.

Fig. 5 illustrates the function of the tongue member relative to the slotted plate member 21 when the hair clip is applied to a strand of hair, indicated at 27, whereby it is apparent from Fig. 5, and indicated generally in Fig. 1, there is formed a ridge 27a of the air intermediate the longitudinal elements 23, 24, of the slotted plate member 21.

The arcuate configuration of the tongue member 25 comprises a central arcuate portion 25b of a larger radius indicated by the symbol R , and end arcuate portions 25c, 25d of lesser radius, indicated by the symbol r , which combined arcuate formations serve to impart pressure by the tongue member 25 relative to the slotted plate member through the intermediation of the strand of hair 27 when the tongue member is in its closed position, as indicated in Fig. 5.

The embodiment illustrated in Figs. 7 through 10 is designated generally 30, and comprises a corrugated non-slotted plate member 31 similarly provided with a tongue member 32, which is hingedly integrally connected at one end 31a of the plate member 31; at the opposite end of the plate member 31 is provided a catch member 33, formed similarly to the catch member 26 of the aforesaid embodiment.

The plate member 31 has a curvature corresponding generally to that of the human head. The tongue member 32 at its central portion 32a has a curvature of a radius greater than that of the plate member 31, the end portions 32b, 32c however of a curvature of less radius as compared with that of the central portion 32a.

By such provision of cooperating configurations, upon applying the hair clip 30 to a strand of hair, as is indicated in Fig. 10, the tongue member 32 when in its locked position, pressure engagement is effected between the central portion 32a of the tongue member relative to the underside of the non-slotted plate member 31, through the intermediation of the interposed strand of hair, thereby insuring maintenance of locking of the hair clip relative to the strand of hair.

I claim:

A hair curler comprising an elongated plate member having a catch member connected thereto at one end and a resilient arcuate-shaped tongue member connected to the plate member at its opposite end, said plate member having a longitudinal slot of a width less than that of the arcuate central portion of the tongue, whereby hair engaged on the tongue is clamped firmly between the edges of said tongue portion and the undersurface of the plate adjacent to the side edges of the slot, in the closed position of the tongue.

WILLIAM HUPPERT.
